FEEDING DEVICE FOR SLUNG SPANGLE MACHINES

Filed Jan. 18, 1946

Fig. 1

UNITED STATES PATENT OFFICE

2,442,220

FEEDING DEVICE FOR SLUNG SPANGLE MACHINES

Maxwell H. Stone, Brooklyn, N. Y.

Application January 18, 1946, Serial No. 641,889

10 Claims. (Cl. 223—48)

1

This invention relates to slung spangle making machines and particularly to the means for feeding and supporting spangles operated upon by the machine.

Such spangles are in the form of thin, centrally perforated discs which are strung on a top thread passing through the perforations of the spangles and held thereby in a pile or stack. Since about 10,000 spangles are arranged in the stack, it will be understood that the stack is of considerable length and must be handled with care. Heretofore, the stack has been supported by inserting the lower end thereof directly into the inlet tube of the machine. Reliance must therefore be had only upon the central or top thread to hold the spangles in the stack in their proper position to be fed to the machine. Said thread is drawn from a suitable spool arranged adjacent the uppermost end of the stack, the thread being unwound from the spool and drawn into the machine along with the spangles at the bottom of the stack. The machine overlaps the individual spangles in succession and reinforces the top thread by means of additional threads arranged lengthwise and along the middle of the rear face of the finished slung spangle strip or ribbon. Other threads such as bobbin or wrapping threads are wrapped by the machine at intervals around the top thread and the additional filler threads, at the rear face of the strip of spangles. None of the five threads mentioned other than the top thread aid in holding the stack of spangles in position for the reason that the additional threads are located at or near the bottom of the stack. The top thread consequently bears all of the load put upon the stack by vibration of the machine and the tendency of the long pile of spangles to sway about and to spill or overturn during the downward movement of the stack into the machine.

The top thread is necessarily as thin as possible so as to be inconspicuous in the finished ribbon or strip of slung spangles and the stresses put upon the thread frequently become too great for the thread to withstand, so that the thread frequently breaks with distressing results. At times, breakage occurs owing to the failure of the unavoidable knots in the thread to pass properly through the perforations in the spangles or through the machine under the pull of the machine, especially when the spangles shift out of alignment in the stack. Such shifting due to vibration, extraneous forces or other causes, tends to wear out the thread with consequent weaken-

2

ing thereof and with a greater tendency to break under stress.

As will be obvious, when the top thread breaks, the sole support for the spangles in the stack is removed, and practically all of the spangles remaining in the stack fly about in all directions and are wasted unless expensive operations to gather and restack them are undertaken.

The present invention therefore contemplates 10 the provision of means for relieving the top thread of much of the load thereon thereby reducing or eliminating danger of breakage thereof, said means also maintaining the spangles in proper alignment.

15 The invention further contemplates the provision of simple means for maintaining the spangles in the stack against disarrangement and loss in the event that the top thread should break, said means rendering it simple and easy to re-thread and stack.

20 The invention further contemplates the provision of means in the form of a tube and a weight slidable along the tube for insuring proper feeding of the spangles in the stack to the machine and speedy and safe loading and reloading of the stack feeding devices when a new supply of spangles becomes necessary.

25 The various objects of the invention will become clear as the description progresses and from 30 the drawings, in which

Fig. 1 is a front elevational view of a slung spangle machine showing my invention applied thereto, the stack-supporting tube being shown foreshortened.

35 Fig. 2 is a side elevational view of the stack-supporting and guiding means and of the slideable stack weight.

40 Fig. 3 is a vertical sectional view of the tube and of the means for holding the threaded stack therein when the tube is not in place on the machine.

45 Fig. 4 is a fragmentary front elevational view of the lower end of the tube.

Fig. 5 is a similar view of the same and of the auxiliary holding and feeding tube for the lower end of the main tube.

50 Fig. 6 is a top plan view partly in section of the stack tube and of the slideable weight used in connection therewith.

55 In the practical embodiment of the invention shown by way of example, the main tube 10 is of the proper innermost diameter to permit the easy insertion of the stack 11 of spangles thereto, while maintaining the stack in proper accurate alignment. The tube is provided with a slot 12

extending throughout the entire length thereof to allow the weighty rod 13 and the supporting member 14 therefor to be easily inserted into the tube and to slide downwardly therein as the height of the stack decreases. The stack weight-
ing device will be described in detail hereinafter.

The lower end of the tube rests on the top of the inlet tube 15 of the slung spangle making machine designated generally by the numeral 16. At its upper end, the tube carries a suitable V-shaped supporting hook or clip, one leg 17 of which is arranged longitudinally of and is secured to the tube, the other leg 18 of the clip outstanding at a convenient angle to permit the clip to be easily and removably hooked over a suitable support such as a fixed pin 19 or the like. To maintain the lower end of the tube 10 in place, an auxiliary tube 20 is provided. The lower end of the tube 20 is flared outwardly to fit around the machine inlet tube 15 and is suitably notched as at its end edge 21 to rest properly on the horizontal post 22 which carries the inlet tube. The upper end part 23 of the auxiliary tube is also flared outwardly to permit the lower end of the tube 10 to be readily telescoped thereinto when the machine is to be loaded. The longitudinal slot 24 in the tube 20 is preferably aligned with the slot 12 of the tube 10 when the feeding device is in operation whereby the weighting rod 13 may move downwardly close to the top of the inlet tube 15 and whereby the stack may be adequately inspected. Obviously, by its engagement with the inlet tube of the machine, the auxiliary tube maintains the lower end of the stack tube 10 removably in its proper position for feeding the spangles of the stack, while permitting quick removal of the stack tube when the machine is to be reloaded.

As has been hereinbefore indicated, the weight-
ing rod 13 is arranged within the stack tube to slide therein and to press downwardly upon the top of the stack 11, thereby to insure proper feeding of the spangles to the machine 16. Said rod has a longitudinal central hole 25 therein for the passage therethrough and through the stack 11 of the top thread 26, and also has a longitudinal slot 27 therein meeting the hole 25. The rod 13 is weighted by the weights 28, 29 arranged outside of the tube 10 and joined to the rod 13 as by means of the twisted plate 14. The inner vertical end part 31 of the plate passes through the slot 12 and is secured to the rod 13, while the other horizontal end part 32 is interposed between the reduced lower end part 33 of the upper weight 28 and the upper end surface 34 of the lower weight 29, the parts being secured together as by means of the screw 35. To mount the weighting device in place, it is first lifted to a point above the tube 10, then moved transversely to insert the top thread through the slot 27 and into the hole 25, whereafter it is moved downwardly to insert the rod 13 through the outwardly flared upper end 30 of the tube 10 until the rod rests on the top of the stack 11, the plate 14 during such movement passing through the tube slot 12. The stack is thus weighted at its top only to insure feeding of the spangles into the machine 16.

Said machine may be of any type suitable for the intended purpose of sewing the spangles into overlapping relation and into strip or ribbon form. As shown generally, the machine comprises a pair of bobbin-carrying discs 36, 37 continuously rotated in opposite directions as by means of the belt 38, belt pulley 39 and suitable gearing interposed between the pulley shaft and the discs. The bobbin threads 40 and 41 are un-

wound from a bobbin as 42 carried by each of the discs, the threads being led as by the pulleys 43 into position to be wrapped at intervals and in opposite directions around the top thread and around a pair of filler threads as 43, 44 led by the pulleys 45 into the machine along the rear faces of the overlapped spangles. The belt 46 operates the pulley 47 on the shaft 49 to which are operatively connected the various mechanisms which pull the thread and the spangles into the machine.

As the machine operates, the various threads are drawn thereinto, the spangles are overlapped and the threads wrapped as described to produce the elongated continuous strip of slung spangles. When the stack is exhausted, the operator stops the machine, removes the empty tube 10 and its spool of thread 26, and replaces the empty tube with another tube 10 containing a stack of spangles strung on a thread 26 which passes through the tube and is wound on another spool. The lower end of said thread projects from the tube and is inserted into the machine ready to be pulled thereby when the machine is again started.

When apart from the machine, the spangles are maintained in the tube 10 by a suitable headed pin such as the nail 50 passing through the perforation 51 at the lower end of the tube, the nail also passing through the slot 12. The top thread 26 is passed through the stack by means of a suitable long needle which draws the thread downwardly from the spool a sufficient distance to provide a free end part on the thread adapted for insertion into the machine.

When re-loading the machine, the lower end of the filled tube 10 is set into the upper end of the auxiliary tube 20, and the top of the tube 10 hooked by its clip or hook on to the pin 19 while the spool carrying the excess thread 26 is suitably supported to permit the thread to be fed as required. The nail 50 is then removed, thereby allowing the tube and the stack to drop into position for feeding, and the weighting rod 13 arranged in the tube as previously described. The machine thus re-loaded may now again be set into operation.

It will be seen that the re-loading operation may be quickly performed by unskilled persons, that no great care need be taken during such operation since the spangles are at all times properly held, that the stack tube maintains the spangles in proper alignment, that should the top thread break for any reason, the stack nevertheless remains in place in the tube and may readily be manipulated if required during the re-knotting of the thread and the restrung of the spangles by the insertion of the nail 50 into the stack tube, that knots in the thread are easily drawn through the stack and the machine when necessary owing to the accurate alignment of the spangles, that the stresses on the top thread are reduced to a minimum by the reduction of transverse movement or swaying of the stack, that the weight on the stack moves automatically as the stack is depleted and acts directly upon the top of the stack at all times, and that I have provided a feeding device well adapted to feed spangles and articles of similar nature which are difficult to handle to machine for further operation thereon.

While I have shown and described certain specific forms of the invention, it will be understood that obvious changes may be made therein within the spirit of the invention defined in the appended claims.

I claim:

1. A spangle feeding device comprising an

elongated tube having a longitudinal slot therein and having a perforation adjacent an end thereof and diametrically opposite the slot, a removable headed pin in the perforation having a shank extending through the slot and adapted to support a stack of threaded spangles arranged within the tube, and a hook clip at the other end of the tube adapted to engage a fixed support to secure said other end in place removably, said clip having a closed upper end and being open at its lower end whereby the clip and the tube are removable as a unit from said support by a lifting movement.

2. A spangle feeding device comprising a tube having a slot throughout the length thereof, means at the end of the tube to support the tube and weighting means slidable along the tube and comprising a rod insertable within the tube and having a longitudinal hole therein communicating with a longitudinal slot in the rod, a weight in transverse spaced relation to the rod, and a member connecting the rod and the weight and adapted to pass through the slot of the tube.

3. A spangle feeding device comprising a first slotted tube, a second shorter slotted tube into which the first tube is adapted to telescope, and weighting means for a stack of spangles within the first tube, said means including a stack-pressing element insertable into the first tube, a weight adapted to be arranged outside of and in spaced relation to the first tube and a connecting member joining the weight and the element.

4. A spangle feeding device according to claim 3 in which the upper end of the first tube is outwardly flared, and both ends of the second tube are outwardly flared.

5. The combination with a slung spangle machine of the character described having an upstanding tubular inlet for spangles and a horizontal post carrying the inlet, of a spangle feeding device comprising a first slotted tube adapted to hold therewithin a stack of threaded spangles, said tube resting removably and loosely on the upper end of the inlet and having a pin-receiving perforation adjacent the lower end thereof, and a second slotted tube receiving the lower end of the first tube and removably encompassing the inlet and thereby aligning the tubes and the stack with the inlet, said second tube having a notched end edge resting removably on the post.

6. The combination with a slung spangle machine of the character described having a spangle inlet, a pair of discs rotatable in opposite directions, a thread carrying bobbin on each disc, a pulley on each disc directing the bobbin thread toward a predetermined point to wrap said thread around the filler threads hereinafter mentioned on the rotation of the discs, and filler thread pulleys directing filler threads toward the inlet, said machine operating to overlap threaded spangles fed thereto and to secure and wrap the bobbin threads on the under side of the length of overlapped spangles, of a tube slotted along

its entire length to split the tube, said tube being adapted to hold a stack of threaded spangles in alignment with the inlet and resting removably on the inlet, and means for supporting the upper end of the tube for removal from the machine by a single movement.

7. A spangle feeding device comprising a tube having a slot along the entire length thereof, a hook clip at one end of the tube, there being a perforation in the tube adjacent the other end thereof, and a weighting device having a part 10 slidable in the tube and having a weight in transverse spaced relation to said part and connected thereto.

8. The combination with a slung spangle machine adapted to overlap threaded spangles into strip form and to wrap threads around filler threads arranged lengthwise along the under side of the strip of overlapped spangles, of a slotted threaded-spangle holding tube, means for supporting the lower end of the tube adjacent the machine and means for supporting the upper end of the tube, both of said means being adapted to permit the removal of the tube from the machine by a single movement.

9. The combination according to claim 8 in which the machine is provided with an inlet member supporting the tube and with means for feeding the filler threads and for feeding and 20 wrapping the wrapping threads around the filler threads.

10. A spangle feeding device comprising a tube having a slot along the entire length thereof and a hook clip at one end of the tube, there being a perforation in the tube adjacent the other end thereof, said clip being closed at the top and open 35 at the bottom thereof whereby the clip may be hooked about a pin by a downward movement and lifted from the pin by an upward movement, and a second slotted tube receiving the first mentioned tube with the slots of the tubes in alignment, said second tube having a notched end edge of generally V-shaped form adapted to rest on the cylindrical surface of a horizontal post 40 of a slung spangle machine.
